UNITED STATES PATENT OFFICE.

GUSTAV EISNER AND FRITZ WÖRZ, OF MUNICH, GERMANY.

MALT-TURNING APPARATUS.

SPECIFICATION forming part of Letters Patent No. 766,230, dated August 2, 1904.

Application filed October 20, 1903. Serial No. 177,820. (No model.)

To all whom it may concern:

Be it known that we, GUSTAV EISNER and FRITZ WÖRZ, subjects of the King of Bavaria, residing at Munich, Germany, have invented 5 certain new and useful Improvements in Malt-Turning Apparatus for Simultaneous Upper and Lower Cuts, of which the following is a specification.

This invention relates to improvements in 10 malt-turning apparatus for simultaneous upper and lower cuts.

The apparatus hitherto known for the purpose of turning germinating grain (green malt) on the floor of the malt-house by means 15 of mechanically-operated shovels or rakes instead of by means of hand-shovels are based on the arrangement of a long horizontal crane placed across the malting-floor approximately one meter above the layer of grain, which is 20 spread over the said floor in the thickness of approximately five centimeters, each end of the crane being supported by means of wheels on a rail fixed to one wall of the malting-house. From this crane are suspended several 25 large and broad shovels, each consisting of a row of blades placed side by side. The crane also carries mechanism for operating the said shovels and reversing them and the like and for moving the crane, the said mechanism being driven by electricity. The crane is thus adapted to move slowly over the malt layer, while the shovels below it are given an ascending and descending movement by means 30 of rotating cranks connected to the rake-holders and a rocking movement by means of special mechanism provided for that purpose. The downward movement causes the shovels to cut into the malt in an inclined direction. By a separate movement, almost simultaneously imparted to the shovels, the points of 35 the blades are slightly elevated, (upward rocking motion,) so that the malt lifted remains on the shovels till it is thrown off above the malt layer by the centrifugal force due to the horizontal rotation of the blades. The ventilated 40 disturbed malt behind the turning apparatus forms the turned layer. The mechanism which imparts to the rotating shovels the rocking movement, so that during the lower 45 part of their circular movement in and through

the malt layer the blade-points receive, so to speak, a certain independent relative movement, may be called the "rocking" mechanism. This independent movement of the shovel on its support while it is circularly ascending 55 and descending with the said support converts the movement of the blade-points into an elliptical one. The shovel movement can be made deeper or shallower and the malt can be thrown off at a greater or less elevation 60 above the floor, as required. This depends on the kind of malt being treated—that is to say, the stages of its germination, of which there are several. Since the germinating grain must not be injured, the blades of the shovels are formed 65 of long flat narrow metal bars or plates fixed only at one end or at the center, so that they are resilient. If the blades are fixed at their centers, both halves thereof can be used. In this case the two halves of the blades are given different shapes, one half of each blade being flat, so that they come flatly into contact with the floor, whereas the other half on the other side of the point of attachment is twisted, so that instead of its broader surface its narrower edges 70 are in the working position. The blades placed edgewise serve more particularly for loosening the malt layers, into which they penetrate more easily than the plates or bars placed broadside on. Of the malt-turning machines 75 described above, which only work with single shovels, some are so arranged that the shovels do not penetrate to the entire depth of the layer, but only to one-half or two-thirds of the said depth, so that they first remove an upper layer and after discharging 80 same pick up the second layer below. The object of this is to ventilate and loosen the malt as thoroughly as possible. This method of working is, however, very inconvenient, 85 since the crane must be given alternate forward and backward movement during its travel by means of reversing-gear, and a large amount of adjustment is necessary. After the first forward movement of the traveling crane 90 and the upper stroke and removal of the upper malt layer the turning apparatus is lifted by means of a gear and the forward movement is converted into a rearward movement extending through half the distance previ- 95 100

ously traveled. The shovels are then automatically adjusted in a lower position in order to pick up the rest of the layer during the lower stroke. A series of movements are therefore required for this operation—forward movement of the turning apparatus, rotation of crank for upper stroke, cessation of the crane movement and reversal of gear, rearward movement, adjustment of the shovel in a lower position, rotation of crank for lower stroke, and, finally, repeated forward movement of the entire apparatus through a distance equal to that first traveled. This arrangement and working gives excellent results, but requires a considerable amount of time.

In the second kind of malt-turning machine the arrangement is such that the crane advances uninterruptedly, the shovels cutting the entire depth of the layer. This method requires less time; but the malt is only lifted by separate short strokes and no particularly thorough loosening and ventilation of the mass is produced by the turning.

The object of the improved apparatus to which the present application relates is to perform the upper and lower strokes simultaneously by means of an arrangement of double shovels, the travel of the crane being uninterrupted. The thoroughness of the turning and ventilation is by this means increased; even as compared with the first of the methods described above, a more considerable length of stroke is rendered possible, a large number of manipulations are dispensed with, and the time required is further reduced only ten minutes, for instance, being required as against twenty minutes and thirty minutes in the case of the older apparatus. A considerable effect is also produced by the fact that the throwing of malt from two shovels containing the malt picked up by the upper and lower strokes at the same time causes the malt on the said shovels to be effectively mixed, besides producing the usual turning of the lower layers to the top. By this means—that is to say, by the increased access of oxygen—the uniform growth of the malt is considerably favored, so that an advantage is obtained in this respect also. The efficiency of the turning apparatus is thus considerably increased.

Figure 1 is a cross-section, partly on the line A B of Fig. 3, showing one of the carriers with the operating-cranks connected to the crane and the new shovel arrangement. Fig. 2 is a cross-section on the line C D of Fig. 3. Fig. 3 is a rear view of the apparatus with the blades of the shovels partly broken away. Fig. 4 is a view corresponding to Fig. 1 with the shovels in the reversed working position, and Fig. 5 is a diagram illustrating the upward and downward movement of the shovels during their circular oscillations. Figs. 6 and 7 illustrate as an example one form of the ap-

paratus in connection with which the shovels and their operating-gear are used, Fig. 6 being a partial front view and Fig. 7 a cross-section near one of the depending shovels.

The shovel-carriers *c* are vertically suspended at intervals from the cranks *b*, which are adapted to be revolved by the gear-wheels *a*. During their upward and downward movement these shovel-carriers describe the circle *d*, as shown in Fig. 5. Besides taking part in the ascending and descending motion the shovels receive independent motion with regard to their carriers, (rocking motion,) as already stated, this independent motion being produced in the known manner by means of an eccentric or crank *e*, a connecting-rod *f*, and an arm *g*.

In the carrier *c* of each shovel a rotatable axle *h*, preferably tubular, is mounted. The length of this axle is approximately equal to the breadth of the shovels, the said breadth being determined as desired. Near each end of this axle is mounted a rotatable sleeve, to which is fixed an arm *i*, the said sleeve being adapted to be fixedly connected to the axle by means of a screw. Each end of each of the said arms is connected to the end of the other arm by means of a rod or axle *k*, from which the shovels *l l* are suspended by means of short rotatable connecting-pieces. Each shovel consists of a series of blades of any suitable shape fixed to a cross-bar, as shown in Figs. 1 and 3.

On the axle *h* are adjustably mounted, by means of sleeves, two hand-levers *m*, Fig. 2, adapted to be fixed in position by means of screws. Each of these hand-levers *m* is provided at its lower end with a short arm. The connecting-piece supporting each shovel is provided with a rigid arm *n*, so that it forms a kind of bell-crank lever, which is connected, by means of a rod *o*, with the arm of one of the levers *m*. By moving the latter the arm *n* and the axle *h* are therefore rotated so that the shovel can be adjusted as required. The fixing of the shovels in the desired positions is effected by fixing the sleeves of the levers *m* to the axle *h* by means of screws.

The adjustment of the forks with regard to the malting-floor depends partly on the depth of the malt layer and partly on other circumstances. The normal adjustment of the forks for the double stroke serves for turning green malt in all stages of growth. In this position the shovel for the lower stroke is adjusted at an angle of approximately thirty-two degrees with regard to the floor when sliding on the latter. The position of the forward shovel for the upper stroke is then as indicated by 1 and depends on the depth of the malt layer, the distance of the blade-points from the floor being approximately one-third of the said depth. The inclination with regard to the floor is then approximately seventy-five degrees. With malt layers of greater depth the distance of the shovel from the floor is in-

creased. Position 2 of the forward shovel is for the loosening of malt with long interlinked radicles, the shovel being lowered to approximately ten millimeters from the floor. Position

5 3 is only necessary before the adjustment from the position shown in Fig. 2 to that shown in Fig. 4 in order to prevent contact with the floor. During this movement the blades of one shovel pass between those of the other.

10 When the shovels have been properly adjusted for double-shovel work, the rocking of the shovels at the proper moment by means of the eccentric-rod f is effected in such a manner that immediately after entering the malt layer

15 the shovels are moved into a casting-off position away from the floor, the shovel for the upper stroke also being moved into the best position for casting off at the moment when the lower shovel leaves the floor. Higher or

20 lower strokes can, however, at all times be arranged according to the stage of growth of the malt, and the rocking motion of the shovels can be increased or reduced in order to increase or reduce the height and distance

25 through which the malt is thrown and the amount of oxygen which it receives.

The rocking or oscillation of each pair of shovels—that is to say, the independent movement by which the shovels are moved from

30 substantially vertical positions to substantially horizontal positions and from the latter back to the former while they are revolving with the entire support—is produced in the known manner, as is also the reversal of the

35 shovels after the apparatus has traveled over the floor, so as to adjust the shovels from the working position shown in Fig. 2 to that shown in Fig. 4, or vice versa. For the better comprehension of these arrangements and the rest

40 of the apparatus the following may, however, be mentioned.

The rod f , to which an upward and downward stroke is imparted, is connected to the arm g , which is fixed to the axle h by means

45 of a sleeve. The short upward and downward movements of this arm are therefore transmitted to the arm i and the shovels; so that the latter are rocked. To the sleeve carrying the arm g is fixed a bearing for a worm s .

50 Within the sleeve there is rigidly fixed to the shaft h a worm-wheel, with which the said worm is in gear. When the binding-screw in the sleeve has been unscrewed, the axle is disengaged from the sleeve, and since the arm

55 and the worm are held by the rod f rotation

of the worm will cause the axle to rotate with the arm i and the shovels, so as to move the latter from one working position to the other,

Fig. 2 or Fig. 4.

60 Regard must be had to the difference between the three movements that work simultaneously and the other two that work only occasionally. The latter movements are the adjustment of the shovels by means of the le-

vers m and their reversal from one working position to the other by means of the worm s . The simultaneous working movements are indicated in Fig. 5, in which the horizontal arrow indicates the travel of the crane, (the working direction,) the arrow in the circle d the direction of the crank motion, with which the supports c and shovels ascend and descend, and the vertical arrows the movement of the connecting-rod f for the independent movement of the shovels. The malt is thrown from the forks in approximately the directions indicated by the two inclined arrows.

Referring to Figs. 6 and 7, the crane referred to at the beginning of this specification comprises a frame F , which supports apparatus for its own locomotion and for moving the shovels. This frame is provided at each side with suitable wheels or rollers R , by means of which it is adapted to roll on rails S , fixed to opposite walls of the malting-house, so that the crane extends across the malting-floor B . The motor-shaft W is connected, by means of a train of gear-wheels a , to the cranks b , by means of which the shovel-carriers c are operated in the manner already described. It is not deemed necessary to describe this part of the apparatus in detail, since it can be of any suitable construction, and the form illustrated is only shown as an example.

Apparatus of the kind described for turning malt can also be used for other purposes for which it is necessary to turn, mix, and ventilate material.

We claim—

1. In apparatus for turning malt and other material, the combination of a pair of shovels adapted to be moved in a horizontal direction over a malting-floor, means for raising and lowering the shovels to and from said floor at relatively different distances therefrom, means for imparting a common rocking motion to said shovels, means for separately adjusting the angle of inclination of the latter, and means for reversing the working position of said shovels substantially as described.

2. In apparatus for turning malt and other material, the combination of a pair of shovels adapted to be moved in a horizontal direction over a malting-floor, means for raising and lowering the shovels to and from said floor at relatively different distances therefrom, means for imparting a common rocking motion to said shovels, a system of hand-operated levers and rods adapted to separately adjust the angle of inclination of the shovels, and means for reversing the working position of the latter substantially as described.

3. In apparatus for turning malt and other material, the combination of a pair of shovels adapted to be moved in a horizontal direction over a malting-floor, and adjustably mounted on a rotatable double-armed-support, means for raising and lowering the shovels to and

from said floor at relatively different distances therefrom, means for imparting a rocking motion to said support, a system of hand-operated levers and rods adapted to separately 5 adjust the angle of inclination of the shovels and means for reversing said double-armed support and consequently the working position of the shovels substantially as described.

In witness whereof we have signed this specification in the presence of two witnesses. 10
